UNITED STATES PATENT OFFICE.

ABEL HUREAU DE VILLENEUVE, OF PARIS, FRANCE.

IMPROVEMENT IN AIR AND GAS ENGINES.

Specification forming part of Letters Patent No. 124,671, dated March 19, 1872.

To all whom it may concern:

Be it known that I, ABEL HUREAU DE VILLENEUVE, of Paris, France, have invented a new Improvement in Machinery for Generating, Obtaining, and Applying Motive Power; and I do hereby declare the following, when taken in connection with the accompanying drawing and the letters of reference marked thereon, to be a full, clear, and exact description of the same, and which said drawing constitutes part of this specification, and represents, in—

Figure 1, a general plan of an engine of ten or twelve horse-power driven by naphtha, methylated or other spirit, at a pressure of about ten atmospheres; Fig. 2, a transverse section of the heating-chamber; Fig. 3, a transverse section through the cylinder of the engine; and in Fig. 4, a longitudinal view of a vertical heating-chamber.

My invention consists of means and apparatus for utilizing, first, the gases arising from the combustion in a closed vessel and under high pressure of all liquid hydrocarbons, whether capable of vaporization or not, which combustion takes place in the presence of compressed air of a high temperature; second, the vapors arising from the injection of volatile liquids, which, while greatly increasing the volume of gas, increase the temperature of the mixture to from 200° to 400°. When the liquids are vaporizable at a lower temperature than 300° they are contained in a jacket around the cylinder of the engine, where, while they prevent the overheating of the metals and lubricating-oils, they utilize the heat subtracted from the hotter gases by being themselves vaporized under pressure. These vapors are introduced by a platinum-rose into a heating-chamber, where they mix intimately, and thence, together with hot air at the same pressure, they pass out through a second platinum-rose, and combustion is caused by their passing over a red-hot platinum-sponge, used to produce or increase the combustion. When the liquids cannot be vaporized at a lower temperature than 300° (such as the heavy oils of petroleum) they are always admitted to the casing around the cylinder, to absorb there a certain part of the heat of the gas; but they are sent in a liquid state into the heating-chamber by means of a small pump. The small streams of liquid which pass

out of the rose are always burnt by the compressed air in passing over the red-hot platinum-sponge. In either case the immense temperature thus developed requires reducing. I therefore inject, by means of a pump opposite the point where the combustion takes place, a volatile liquid, which, while it reduces the temperature, increases the volume of the gaseous mass.

In most cases the liquid, before entering by a pump or by a perforation in the heating-chamber, may be raised to a temperature of about 100° by the gas which is emitted from the cylinder and by the heat developed by the compression of air in the air-pump. The compressed air from the air-pump is reheated in a casing placed around the heating-chamber. This heating of the air will produce a quicker combustion, and therefore the combustible material will be burned with as little air as possible. In order to diminish the work of the air-pump, instead of passing therethrough compressed air, I can pass oxygen produced by the decomposition of salts of manganese, chlorates, or other means, and in order to utilize the gas to a greater extent a valve is used.

This invention will be clearly understood by referring to the accompanying sheet of drawing, in which Fig. 1 is a general plan of an engine of ten or twelve horse-power, driven by naphtha, methylated or other spirit, at a pressure of about ten atmospheres.

A represents the cylinder with its casing in section, (partly shown in transverse section, Fig. 3.) The said casing contains the liquid to be vaporized, the cylinder, the valve, and the exhaust-pipe *f* immersed in the liquid. The casing has at its upper part a steam-space, and at one side a gauge-tube, *N*, which is also used for putting the apparatus in motion. Below the water-level on this tube is seen a copper ball, containing a small quantity of liquid to be vaporized. The cocks *r* and *r'* being closed, the ball is heated by a lamp, and the vapor therefrom enters the heating-chamber by the tube *t*. *E* is the force-pump for inducting the combustible liquid with the casing. *b* is the tube for the passage of the combustible vapor. *C* is the air-pump; *D*, the pump for forcing the air into the heating-chamber; and *d* conducts water to the heating-chamber.

Fig. 2 is a transverse section of the heating-

chamber, which is lined inside with refractory clay, *e*. Near the lower end are two tubes furnished with platinum-roses, one of which, *m*, introduces the combustible vapors, and the other, *b*, this compressed air. The platinum-sponge *p*, heated to a red-heat by a central interior blow-pipe, produces and keeps up the combustion. At the other end is the rose or perforation through which the injection water passes. The mixture of gas and steam escapes by the tube *a* from the dome at a temperature of about 200° to 400°, and is delivered to the valve of the cylinder.

Fig. 4 represents a longitudinal view of a vertical heating-chamber. Into this cylindrical generating store (constructed of copper) the compressed air enters through the pipe *B* placed at the lower end. The tube *C* is used for lighting purposes. The air and combustible matter meet together over a platinum-sponge, *P*, or a piece of lime placed upon a cap, *a*. The air is heated upon the perforated slabs in the pipe *A*, and combustion takes place continuously in the furnace *D*, whence the products of combustion pass through the small holes *E E* to escape by the tube *F* into the motive-cylinder. Water is also admitted through the pipe *G*, and, passing through *H*, flows along the spiral *I*, fixed upon the cone over the furnace, through which said cone are pierced the holes *E E*. The quantity of water admitted should be regulated so that the whole of it is vaporized before reaching the bottom of the cylinder; but if any excess of water enters it will gravitate through *K* into a suitable reservoir for its reception. The steam

produced from this water is superheated by mixing with the products of combustion, and passes with them into the cylinder to work the piston. It would be possible, with a slight modification, to burn solid combustible matters in this way, which would be introduced into the furnace by means of a chute.

It will be understood that the arrangement of apparatus above described is only shown as a specimen of the invention, but the said apparatus may be modified to adapt itself to circumstances; the object of the invention being to diminish the weight of the fuel employed, (a most important item in marine and aerial navigation,) and to diminish also the weight of the machine per horse-power.

I claim as my invention—

The apparatus above described, consisting of the cylinder *A* with its outer case or jacket, forming a chamber around the said cylinder to receive the liquid to be vaporized, the said cylinder and its valve and exhaust-pipe submerged in said chamber, the force-pump *E*, air-pump *C*, and force-pump *D*, and their connection with the generating heating-chamber, where, in the presence of compressed air, combustion and vaporization of liquids and fluids used as auxiliaries to the motive-power takes place.

In testimony whereof I have signed my name to this specification before two subscribing witnesses.

ABEL HUREAU DE VILLENEUVE.
